ANIMAL CHUTE

Christian Grabe, San Jose, Calif.

Application September 11, 1935, Serial No. 40,063

4 Claims. (Cl. 119—155)

The present invention relates particularly to a portable and adjustable chute for use in connection with the segregation of sheep and the like.

There are many various circumstances where it is desired to separate from a common flock or herd of animals those having a given characteristic. For instance at shearing time it may be desired to separate the lambs from a flock of sheep, or in the case of the sale of certain stock it may be desired to separate the fat from the lean.

The process of effecting the desired separation in any such case is ordinarily rather a slow and difficult one, and is particularly so in yards where various flocks and herds are quartered and separating corrals are limited.

It is one object of the present invention to provide portable and adjustable means whereby separation may be quickly and easily effected at any point in the yards without material alteration in the existing structure.

It is also an object of the invention to provide means of the character indicated that will be economical to manufacture, simple in form and construction, light in weight, quickly and easily positioned and adjusted, and highly efficient in its practical application.

In the drawing:

Figure 1 is a plan view of a structure embodying my invention operatively disposed in a cattle yard.

Figure 2 is an enlarged detail illustration of a means for mounting the swingable portions of the structure.

Figure 3 is an end elevation of one of the members composing the structure, with parts broken away.

In the particular embodiment of the invention herein disclosed, I show at 1—1 the two fences forming the sides of a lane or runway 2. The fences are provided with the usual openings as at 3 normally closed by means of gates as 4 swingably mounted on the fence structure as at 5. At 6 are indicated portions of other fences cooperating with fences 1—1 to form corrals as 7.

In effecting my invention as herein disclosed I provide four separate fence sections as indicated by the reference characters 8, 9, 10 and 11, the sections 8, 10 and 11 being relatively short and of substantially the same size and the section 9 being substantially three times the length of the other sections and forming the main body of the structure.

The fence section 8 is swingably mounted on fence 1 by means of separable hinges of any suit-

able type such as an eye-bolt 12 mounted in the stationary fence and a hook 13 mounted in section 8. By means of this construction the section 8 may be moved about the yards and quickly mounted at any point where the eye-bolts have been placed. In the other edge of the section 8 and opposite to the hooks 13 are mounted eye-bolts as at 14.

The longer central section 9 of the portable fence is fitted with hooks as at 15 adapted to engage the eye-bolts 14 in section 8, and its opposite edge is likewise provided with eye-bolts as indicated at 16. Upon this latter end of section 9 is also mounted a vertically disposed stake or bar 17 as at 18 with its lower end extending below the bottom edge of the section so that it may be seated in the ground as at 19 to fixedly secure the section 9 in position.

The section 10 functions as a gate and is fitted with hooks as at 20 adapted to engage the eye-bolts 16 in section 9 and swing thereon.

The section 11 also functions as a gate and is fitted with hooks at 21 adapted to engage eye-bolts 22 mounted in gate 4 to swing thereon. The gate 4 is fitted with a vertically disposed stake 23 at 24 on its unattached end whereby it may be secured against movement.

Assuming that the lambs are to be separated from a flock of sheep and assembled in the one enclosure or corral 7, the section 11 is mounted on gate 4 as described and the gate 4 is secured in the position shown by driving the stake 23 into the ground. The section 11 now functions as a gate controlling the opening 3 into corral 7.

The section 8 is now mounted on the fence 1 on the opposite side of the lane 2 and the long section 9 is mounted on section 8. Then the section 10 is mounted on section 9 and the sections 9 and 10 are adjusted so that the section 10 will take the position shown in solid lines and the stake 17 is driven into the ground to hold the section 9 rigidly in position. The section 10 now functions as a gate controlling the passage of animals from the lane portion 24.

By means of this construction the sheep moving down lane 2 in the direction indicated by the arrow 25 must necessarily pass into the lane portion 24, and with the section 11 closed and the section 10 open as indicated in dotted lines at 26 they may pass along into the lower portion of the lane. But when one or more lambs reach this point of separation the section 11 is swung open as indicated in dotted lines at 27 and they must necessarily pass on into the corral, after which

35

55

the section 11 is again closed and the way is again opened to the lower portion of the lane.

With the two sections 10 and 11 pivoted in the positions shown the diversion of the lambs from 5 the main flock is an easy matter because with the section 10 wide open the operator of the gates can stand on the inside of gate 11 and open it to any desired extent to let one or more lambs through.

By merely shifting the several sections into 10 the position shown in dotted lines at 28 the structure may be used in connection with another corral, and so it may be shifted up or down the lane 2 or to any other portion of the yards.

It is to be understood, of course, that while I 15 have herein shown and described but one specific embodiment of the invention, changes in form, construction, and method of assembly and operation may be made within the scope of the appended claims.

20 I claim:

1. The combination with the fences defining 25 the sides of a lane and provided with an opening having a swingable closure, of a plurality of hingedly connected fence sections disposed angularly across the lane to form a restricted passage, with one of said sections being disposed to 30 form a swingable closure for said passage, means for fixedly supporting the other sections, means for fixedly supporting the first named closure in an open position and a section hingedly mounted on the first named closure and swingable into overlapping relationship with the second named swingable closure.

2. The combination with the fences defining 35 the sides of a lane and provided with an opening having a swingable closure therefor, of a central

fence section, an end fence section swingably and detachably connected to one end thereof and swingably and detachably connected to one of said side fences, supporting means for fixedly positioning the other end of the central section, a 5 gate section swingably mounted upon the last named end of the central section and detachable therefrom and movable toward the other side fence adjacent the opening therein, and a fourth section swingably and detachably mounted upon 10 the free end of the closure for said opening to swing into overlapping relationship with said gate section, and supporting means for fixedly positioning the free end of said closure in an open position. 15

3. The combination with the fences defining the sides of a lane and provided with an opening having a swingable closure, of a removable fence structure disposed angularly across the lane to form a restricted passage and having a gate disposed thereon to form a swingable closure for said passage, means for fixedly supporting the first named closure in an open position, and a gate hingedly mounted on the closure and swingable into overlapping relationship with the first 25 named gate.

4. The combination with the fences defining the sides of a lane and provided with an opening having a swingable closure, of a removable fence structure disposed angularly across the lane to 30 form a restricted passage and having a gate disposed thereon to form a swingable closure for said passage, and a gate mounted on the first named closure to swing into overlapping relationship with the first named gate. 35
